UNITED STATES PATENT OFFICE

165,364

PICTURE FRAME

James Clayman, Allston, Mass.

Application March 30, 1950, Serial No. 8,881

Term of patent 7 years

(Cl. D29—20)

To all whom it may concern:

Be it known that I, James Clayman, a citizen of the United States, residing at 8 Harvard Terrace, Allston 34, State of Massachusetts, have invented a new, original, and ornamental Design for a Picture Frame, of which the following is a specification, reference being had to the accompanying drawing, forming a part hereof.

Fig. 1 is a front elevational view of a picture frame, showing my new design; and

Fig. 2 is a sectional view taken substantially along line 2—2 of Figure 1.

I claim:

The ornamental design for a picture frame, as shown.

JAMES CLAYMAN.
